UNITED STATES PATENT OFFICE.

JOHN GOOD, OF BROOKLYN, NEW YORK.

LABYRINTH-VALVE.

1,177,946.

Specification of Letters Patent.

Patented Apr. 4, 1916.

Application filed February 2, 1914. Serial No. 815,917.

To all whom it may concern:

Be it known that I, JOHN GOOD, a citizen of the United States, and a resident of Brooklyn, in the county of Kings and State 5 of New York, have invented certain new and useful Improvements in Labyrinth-Valves, of which the following is a full, true, and complete specification.

The improvements relate to the form and 10 structural arrangement of the lamellæ or valve members of labyrinth valves and more particularly to cylindrical labyrinth valves and the means of applying the same to the chamber containing the fluid under pressure, 15 which they are to control.

The invention is particularly useful in internal combustion engines.

In the accompanying drawings forming 20 part hereof, Figure 1 represents an internal combustion engine having the improved valve therein; Figs. 2 and 3 are enlarged axial and transverse sections, respectively, of one of such valves; Figs. 4 and 5 are similar sections of a modified form; Figs. 25 6 and 7 are similar sections of a further modification; and Figs. 8 and 9 are also modifications.

Referring to Fig. 1, the intake and exhaust passages 1, of the engine shown, extend laterally in opposite directions from the upper end of the combustion chamber forming a so-called T-head engine structure, and the casing forming each of these passages is enlarged, as a valve chamber, to 35 receive the valves. These valves are rotary valves rotating on axes which are upright or parallel with the axis of the engine cylinder, although they might be otherwise, forming a general engine design not materially differing in appearance from the common T-head puppet valve type. From the interior of the engine the passages 1 lead through the valves to the manifold connections 2 and 3, which are preferably disposed 40 at the top of said valves, as indicated, and each valve is driven at its lower side by a vertical shaft 4 from the engine crank shaft 5, the gear ratio from the crank shaft to the valve shafts being as desired and in accordance with the arrangement of the ports 45 in the valves, as will later appear. Both valves are assumed to be alike in Fig. 1 and each is comprised of two series of rela-

tively rotary concentric shells of circular cross section, preferably true cylinders, the 55 shells of one series interlapping, without contact, with those of the other series so as to form a very narrow labyrinth crevice between the shells, and the shells of both series are provided with radially aligned port 60 openings which open a free passage through the valve, while in mutual registry, but close such passage when the rotation carries the openings out of registry. The closure of the valve results from the obstruction encountered by the film of gas or fluid in its effort to escape through the narrow labyrinth crevice, such obstruction being due to the friction of the said film upon the surfaces of the shells or cylinders and by the 70 relative rotation of the latter which tends to drag the adhering film away from its shortest path of escape. In the form shown by Figs. 1 to 3, the shells or cylinders of one of the series, marked 6, are concentrically secured, in fixed position, to a cover plate 7, with spacer rings 8 interposed around and between them. The cylinders 9 of the opposing series are similarly secured to a head 10 with spacer rings 11 interposed 75 between them and project toward the cover plate interlapping with the cylinders 6, but without contact with them. The head or part 10 is adapted to be rotated on an axis concentric with that of the cylinders, and for 80 this purpose is supported in or on a bearing 12 and connected with the valve shaft 4, to be driven thereby. The shells or cylinders thus assembled are surrounded by a water-jacket sleeve 13, in which two passages 14 and 15 are provided, on diametrically opposite sides thereof, the passage 15 being 85 aligned with the passage 1, and the passage 14 being connected with the same passage by the semi-circular side passages 14a. 90 The fixed cylinders 6 each have two openings 6a formed therein in radial alinement with these passages 14 and 15, respectively, and the cylinders 9 each have two corresponding openings 9a in a similar arrangement, so that when both sets of openings 95 are aligned, the path through the valve will extend radially inward from opposite sides of the cylinders to the interior of the innermost cylinder and thence axially within 100 such cylinder through the cover plate 7, and

105

thence into the manifold connection 2 or 3. One revolution of this valve shaft thus results in two openings of the valve. It will be observed that when the opposite radial passages through the valves are closed by the rotation of the cylinders 9, such pressure as may then obtain within the engine cylinder has access to opposite sides of the outer or terminal shell of the assembled series, thereby counterbalancing whatever tendency might otherwise exist to press the cylinders to one side, or cause the shaft 4 to bear unduly upon its bearing. Such provisions are not, however, essential to the operation of the device inasmuch as the crevice surrounding the outer shell of the assemblage may be sufficient to distribute the pressure thereover. It will also be observed that the fixed cylinders 6 are readily removable when desired, by removing the cover plate 7 to which they are attached and that the rotary head 10 can be removed through the same opening. When in operation, leakage around the head 10 is prevented by the bearing 12, or by any other suitable means of obstructing flow through such space or crack as may exist between the head and the surrounding casing. The location of the bearing 12 is not of consequence, but when formed by rubbing surfaces, as indicated in the present case, is desirably somewhat remote from the regions that are subject to high temperature, and is preferably placed where it can be oiled when necessary.

Referring now to Figs. 4 and 5, the construction therein illustrated differs from that already described only in the respect that the water-jacket casing 13 is not present and that the series of interlapping cylinders 16 and 17 are each provided with but a single port opening, which is brought into radial alinement once for every revolution of the head 10 and valve shaft 4. When this form of valve is closed, the outermost shell or cylinder of the assemblage is subject to the pressure of the fluid on all sides, the passage 18 being relatively wide for this purpose, although the proportions shown are somewhat larger than necessary. Between the head 10 and the valve casing, there is placed a washer 19, which in this form serves to prevent leakage that might tend to take place at the bearing.

While in both forms above described the pressure of the controlled fluid has access to the outer side of the outer or terminal cylinder of the assemblage, it will be understood that by simple reversal the interior of the innermost cylinder can be exposed to the pressure, if desired, and without in any way affecting the mode of operation of the valve.

It will be evident that the total length of the labyrinth crevice between the cylinders may be made as long as necessary to serve

the particular pressure to be controlled, as, for instance, by using a greater extent of overlap of the shells or cylinders, or a larger number of cylinders, but as such enlargement necessarily also enlarges the diameter of the valve structure as a whole, and is sometimes inconvenient of use on this account, the same effect may be obtained by using two or more assemblages of concentric interlapping cylinders, in series relation. This is illustrated in Figs. 6 and 7, wherein the fixed cylinders 20 of each group or assemblage are secured to a fixed cover part 23 and the complementary rotary cylinders 21 are secured to two adjacent rotary heads 22, both assemblages being inclosed in a common casing 24. This casing forms a chamber for each group of cylinders and also in the present case provides the bearings for the heads. The two chambers in the casing are separated by a partition wall 25, which is desirably a thin wall, and are connected with each other by an opening 25^a in the wall, the latter being alined with the port openings 20^a on the fixed disks 20 of each group.

The rotary cylinders are driven by two intermeshing gears 26, or otherwise, so that their port openings 21^a are brought simultaneously into registry with the fixed openings and the passage 25^a. Either one or both of the gears 26 may be driven by a shaft 4 from the engine crank shaft, or otherwise, and the fluid controlled by the valve may pass axially into one group through the registering passages, and axially out through the other group, as indicated by the arrows.

Moreover, it is within the invention to arrange two groups of interlapping cylinders in the reverse sense, that is to say, that the fluid to be controlled enters from the outside of one assemblage, passes from the interior of that assemblage into the interior of the next, and thence outwardly through the latter. It is furthermore within the invention to provide two assemblages of valves of this type, the second of which will serve as the second assemblage for another valve. Such arrangement is shown in Fig. 8, wherein the primary assemblage of interlapping cylinders marked 27, may have its interior connected with a port 28, and another primary assemblage 29, may have its interior connected to a port 30. Both primary assemblages 27 and 29 are contiguous or adjacent to a single secondary assemblage 31, and the rotary cylinders of all three assemblages are inclosed in a casing 29^a and geared together by gears 33, so that the openings in the single secondary will register successively with the openings in both primaries, at the proper moment thus permitting the fluid to escape alternately from port 28 and 30 into and through port

32 which leads from the interior of the secondary assemblage 31, and in each case effectively closing the passage through the said ports 28 and 29 at other times, as will be evident.

I claim:

1. A labyrinth valve comprising two series of concentric shells, those of one series interlapping without contact with those of 10 the other series and relatively rotary with respect thereto, and each series being provided with radial port openings whereby a free passage is alternately opened and closed by the relative rotation of the shells.
- 15 2. A labyrinth valve comprising a series of cylinders concentrically held in fixed position and a series of rotary concentric cylinders interlapping without contact with the fixed cylinders and both series being provided with alined port openings, whereby a 20 free passage is alternately opened and closed through the valve by the relative rotation of one series with respect to the other.
- 25 3. A labyrinth valve for controlling fluid under pressure, comprising two series of concentric shells of circular cross section, those of one series interlapping with the shells of the other series to form a labyrinth crevice therebetween and both series provided with alined openings whereby a free 30 passage is alternately opened and closed by the relative rotation of the two series and means whereby the fluid under pressure has access to opposite sides of one of the shells, 35 to balance the pressure thereon.

4. The combination of a chamber for fluid under pressure, a valve controlling a passage leading thereto, said valve comprising two series of relatively rotary, concentrically 40 mounted shells of circular cross section, the shells of one series interlapping with those of the other series and provided with radially alined port openings adapted to register with the said passage to open communication through the same means for rotating one of the series of said shells, and means for balancing the pressure on opposite sides of said valve.

5. The combination of a chamber containing fluid under pressure, a valve at one side of such chamber controlling a passage leading thereto, said valve being comprised of two series of relatively rotary, concentric shells of circular cross section, the shells of 55 one series interlapping with those of the other series without contact therewith to form a labyrinth crevice between them, port openings in each series of shells adapted for registration with each other and with said passage and a shaft alined with the common axis of the series of rotary shells for rotating the same.

6. A labyrinth valve comprising two series of concentric shells of circular cross section, those of one series interlapping without

contact with those of the other to form a labyrinth crevice therebetween, port openings in both series of shells adapted for mutual registration, and thereby forming a passage through said valve extending axially through the innermost shell and radially through the said port openings when registered.

7. A valve comprising two series of concentric cylinders, the shells of one series interlapping with those of the other and the shells of one or both of said series being provided with port openings in alinement whereby a free passage through the valve is opened and closed by the rotation of the 75 shells, the innermost shell of the assemblage having a cross-sectional area approximating the area of said free passage through the registering port openings.

8. A labyrinth valve for controlling fluid 85 under pressure and comprising two series of concentric shells of circular cross section, the shells of one series interlapping with those of the other to form a labyrinth crevice therebetween and both series provided with radially alined port openings 90 adapted for registration by the relative rotation of the two series of shells, the terminal shell of one of the series being exposed at diametrically opposite points to the pressure of the fluid controlled by said valve, and a portion of the fluid passage through the valve, when open, extending axially of the shells.

9. A labyrinth valve comprising a valve 100 chamber, two concentric series of shells therein, the shells of one series interlapping with those of the other series and both series provided with port openings adapted to register, whereby a free passage is opened 105 through the interlapping series by the relative rotation thereof, a cover for the valve chamber forming a support at one end of the valve chamber for one of the series of shells and driving means entering the valve chamber on the opposite side for rotating the 110 other series of shells.

10. The combination with an internal combustion engine of a labyrinth valve controlling a passage connecting with the interior of the cylinder thereof and comprising a plurality of interlapping relatively rotary concentric shells having radial port openings therein adapted to form a passage extending radially through the shells and axially through the innermost shell, and a pipe connection with the said innermost shell.

11. The combination with a chamber to contain fluid under pressure, of a valve chamber, a cylindrical labyrinth valve therein comprising a series of ported concentric cylinders fixed within the valve chamber and a series of rotary interlapping concentric cylinders having openings adapted to register with the openings of said first men-

tioned series to form a free passage through the valve, a part supporting the rotary shells, means between said part and valve chamber to prevent leakage of the fluid around the same and means for rotating said supporting part.

12. A valve for controlling fluid pressure, comprising a valve casing or chamber, a series of rotary concentric shells mounted therein, a cover member for said valve chamber, a series of relatively fixed concentric shells secured thereto and interlapping with the fixed cylinders, both series provided with port openings adapted to register and open and close a free passage through the shells by the relative rotation thereof, and a pipe connection with said cover member communicating with the interior of the innermost shell, the organization of the parts being such that on the removal of said cover member and fixed shells, the rotary shells may be removed through the same opening.

13. A valve for controlling fluid pressure, comprising two assemblages of concentric shells, each assemblage comprising a series of relatively fixed and a series of relatively rotary shells interlapping with each other, both fixed and rotary series of each assemblage having port openings therein, adapted for registry to form a free passage through both assemblages of shells.

14. A double valve comprising two primary assemblages of interlapping valve members and one secondary assemblage,

adapted for alternately coöperating with each primary assemblage, each assemblage comprising a series of relatively fixed and a series of relatively rotary valve members having port openings adapted to register to form a free passage through either primary and the secondary.

15. A valve for controlling fluid pressure comprising a rotatable ported valve member and a stationary ported valve member, the two being of circular section and forming between them a continuous narrow crevice adapted by virtue of its narrowness and extent to prevent the escape of said pressure therethrough when said rotatable member is rotating, and means for balancing the pressure on said rotatable member to maintain the alinement thereof.

16. A valve for controlling fluid pressure of high temperature comprising a rotatable ported valve member, a relatively stationary valve member, the two being of circular cross-section and forming between them a narrow non-sealed crevice of sufficient extent and narrowness to prevent escape of pressure therethrough, means whereby said rotatable member is subjected to said pressure in opposite directions, and means for abstracting heat from said valve members.

In testimony whereof, I have signed this specification in the presence of two witnesses.

JOHN GOOD.
